CLAIM

The ornamental design for a collapsible hand-held periscope, as shown and described.

DESCRIPTION

FIG. 1 is a front perspective view of a collapsible hand-held periscope showing my new design;

FIG. 2 is a top plan view thereof;

FIG. 3 is a front elevational view thereof;

FIG. 4 is a side elevational view, the opposite side being a mirror image thereof;

FIG. 5 is a rear elevational view thereof; and

FIG. 6 is a bottom plan view of the periscope.

FIG. 1.

FIG. 2.

FIG. 3.
